UNITED STATES PATENT OFFICE.

ALLISON F. GODDARD, OF RANKIN, ILLINOIS.

FLY-BRUSH.

1,151,174.

Specification of Letters Patent. Patented Aug. 24, 1915.

Application filed September 3, 1913. Serial No. 787,967.

To all whom it may concern:

Be it known that I, ALLISON F. GODDARD, a citizen of the United States, residing at Rankin, in the county of Vermilion and State of Illinois, have invented new and useful Improvements in Fly-Brushes, of which the following is a specification.

This invention relates to fly brushes and more particularly to that type which are adapted to be rotated with each movement of the door.

One of the principal objects of the invention is to provide a simple and efficient device of this character wherein the brushes may be conveniently replaced and wherein the drum is properly guarded to prevent the brushes catching beneath the operating cable.

A further object of the invention is the provision of a device of this character having a tapering brush holding head and a tapering adjusting nut or collar which co-acts to prevent the operating cables from becoming displaced.

Further objects of the invention will appear as the following description is read in connection with the accompanying drawing, which forms a part of this application, and in which:

Figure 1 is a front view. Fig. 2 is a vertical sectional view.

Referring more particularly to the drawing, 1 represents an ordinary door frame to which is hinged a screen door 2 consisting of vertical stiles 3, top and bottom rails 4 and 5, an intermediate rail 6 and a vertical center stile 7. Secured to and running parallel with the vertical stile 7 is a casing which extends to a point approximately reaching the lower edge of the lower stile 5 and slightly above the center rail 6. This casing is arranged to receive the operating weight 9, the function of which will be hereinafter described. Passing through the center stile 7 is a bolt 10 which has journaled thereon a drum 11 provided with a brush attaching head 12 somewhat larger than the drum, the head tapering so as to merge into the drum.

Threaded on the bolt and positioned on

the outer face of the door so as to form an abutment for the drum is a conical collar 13 which serves in the same capacity as the tapering end of the head. Wound around the drum and connected at one end to the weight and at its opposite end to a stationary eye member 14 on the frame 1 is a cable 15 which passes over a pulley 16 journaled in a bracket 17 secured to the top rail of the door. It will, therefore, be seen that when the door is open the weight will be raised and the drum rotated and when the door is released the weight will gravitate and rotate the drum in the opposite direction and also close the door.

Secured to and radiating from the drum are a plurality of brush supporting arms 18, all of which are constructed from a single strand of wire having the elongated loops formed therein, as shown at 19. The separate legs of each loop are arranged in spaced relation so as to permit the connection of the brushes 20 thereto, as shown. At the inner end of the legs of each loop the strands are twisted together and the connecting portion between each arm is preferably embedded in the head 12. The brushes 20 may be constructed of any suitable material but I prefer to use pieces of oil-cloth freely connected to the legs so as to turn thereon and being longitudinally slit, as shown.

Secured to the center stile 6 and lying over the drum is a guard or shield 21 which is apertured on the top to permit the passage of the cable and which is open upon the bottom for a similar purpose. This shield effectively prevents the strips of brush material from engaging beneath the cable on the drum and thereby stopping the operation of the door.

What I claim is:

In a fly brush for screen doors, the combination with a drum mounted on the door and having an operating cable wound thereon, a plurality of brush supporting arms mounted on the drum and each formed of a single length of wire bent upon itself to provide a brush receiving loop, and having the strands of the wire intersecting each other at a point above the connection of the arm

with the drum, and a cylindrical guard surrounding the drum and detachably secured to the door and having one end lying in close proximity to the point of intersection between the strands of brush supporting arms, the said guard being provided with openings for the passage of the cable therethrough.

In testimony whereof I affix my signature in presence of two witnesses.

ALLISON F. GODDARD.
